UNITED STATES PATENT OFFICE

ARTHUR S. WATTS, OF COLUMBUS, OHIO

TEMPERATURE CONTROLLING METHOD FOR CERAMIC FURNACES OR KILNS

Application filed June 19, 1930. Serial No. 462,272.

In the drawings:

Figure 1 is a diagrammatic vertical transverse section of an electrically heated kiln embodying my invention.

Figure 2 is a similar view of a gas or liquid fuel fired kiln.

The reference numeral 3 designates a kiln having a draft outlet, a draft inlet 4 near the bottom of the kiln and a draft inlet 5 near the top of the kiln. An electric heating unit 6 is located in the kiln, said unit being controlled by the rheostat 7 having contacts 8 and a contact arm or switch 9 pivotally mounted. The draft inlet 5 is provided with a damper 10 connected to a pivoted arm 11 which in turn is pivotally connected to the switch 9 by a link 12, so that simultaneous action of damper 10 and switch 9 is assured. The arrows indicate the direction of the draft into and out of the kiln.

In Figure 2 my invention is shown embodied in a gas or liquid fuel fired furnace or kiln in which I provide a draft inlet 13 and a draft outlet 14. Above the inlet 13 I provide an auxiliary air inlet 15. A damper 16 common to the inlets 13 and 15 simultaneously controls these inlets, said damper being moved by a suitably controlled arm 17. The outer end of the inlet 13 is flared and in this flared end is positioned a nozzle like element 18 in the outer end portion of which is positioned a tube 19. It will be noted that the walls of the inlet 13, nozzle 18, and tube 19 are spaced from each other.

In the firing of special porcelains which are of the self-glazing type, the interior of the article is usually fired to a degree of vitrification approaching fusion in order to secure the desired degree of surface density and brilliancy. This is accomplished in the present state of the art by heating the article to a predetermined temperature and maintaining this temperature until the surface displays the desired maturity. This results in a certain loss of detail and a degree of distortion, de-

pending on the composition of the article and the temperature and time necessary to develop the desired surface characteristics.

I have found that if such articles are heated to a temperature slightly below that necessary for the development of the desired surface characteristics and maintained at this temperature for a proper period of time, and if the temperature of the article is then raised abruptly to a temperature slightly higher than that normally employed in the firing of such wares and maintained at this temperature for a very brief period of time, followed by an abrupt moderate temperature drop, the product will possess a superior surface and superior mechanical strength.

To accomplish this special treatment, a suitable kiln or furnace is necessary in which the desired temperatures can be developed and provided with suitable mechanism by which the required abrupt temperature changes can be accomplished.

If electrically heated, these abrupt temperature changes may be accomplished by providing a rheostat control combined with a system of ventilation so that when an abrupt temperature increase is desired the flow of current can be increased and simultaneously the ventilation be decreased, thus reducing the amount of heat lost by draft. When an abrupt temperature drop is desired, the flow of current is reduced and the ventilation increased, thus abruptly reducing the heat introduced and by ventilation, removing a large amount of the heat present. Either or both of these systems may be employed as the case may demand.

If the kiln or furnace is heated by means of solid, liquid, or gaseous fuel the abrupt temperature increase is accomplished by simultaneous increase of fuel supply and reduction of excess air admitted to the furnace. If an abrupt temperature decrease is desired, the fuel supply is decreased and the excess air admitted to the furnace or kiln is in-

creased. At all times, however, the amount of air admitted must be sufficient to give complete combustion, unless a reducing atmosphere is desired.

- 5 The kiln or furnace indicated in the description is of the periodic type in which the ware is placed after forming or after a low temperature biscuit firing to remove carbonaceous matter present, and where it remains stationary throughout the various heating and cooling treatments. The essential features of my invention are—
- 10 (1) The control of abrupt temperature changes by means of the ventilation of the chamber in which the ware is located, the ventilation being decreased for the development of higher temperatures and increased for lowering of temperature. The heat generation remains constant.
- 15 (2) The simultaneous increase of electric current and decrease of ventilation to increase temperature and the simultaneous decrease of electric current and increase of ventilation to decrease temperature.
- 20 (3) The simultaneous increase of fuel and decrease of ventilation to increased temperature and the simultaneous decrease of fuel and increase of ventilation to decrease temperature.
- 25 While I have shown apparatus for the purpose of illustrating my invention it will, of course, be understood that my invention is not limited to such apparatus, the invention being basic in principle as related in the appended claims.

What I claim is:

1. The method of controlling the temperature in a kiln for firing porcelains and similar ceramic products for the purpose of producing desired surface characteristics of the product, which consists in heating the kiln chamber in which the ware is located, and controlling the heating action by abrupt temperature changes by means of the ventilation of the chamber in which the ware is located, decreasing the ventilation for the development of higher temperatures and increasing the ventilation for lowering of temperatures.
2. The method of controlling the temperature in a kiln for firing porcelains and similar ceramic wares for the purpose of producing desired surface characteristics of the product, which consists in heating the ware, and simultaneously increasing the supply of heat and decreasing the rate of ventilation to increase the temperature, and simultaneously decreasing the supply of heat and increasing the rate of ventilation to decrease temperature.
3. The method of controlling the temperature in a kiln for firing porcelains and similar ceramic products for the purpose of producing desired surface characteristics of the product, which consists in heating the kiln chamber in which the ware is located, and

effecting abrupt temperature changes by means of the ventilation of the chamber in which the ware is located, decreasing the ventilation for the development of higher temperatures and increasing the ventilation for lowering of temperatures while maintaining the heat generation constant.

4. The method of firing porcelains of the self-glazing type in a kiln or furnace for the development of desired surface characteristics, which consists in firing the article to a degree of vitrification approaching fusion by heating the article to a temperature close to but below surface fusing temperature and maintaining such temperature for a predetermined period of time, then abruptly raising the temperature to a degree above the surface fusing point and maintaining the same until the desired surface characteristics are produced, and then abruptly reducing the temperature to a degree below the surface fusing point.

5. The method of furnace or kiln firing porcelains of the self-glazing type for the development of desired surface characteristics, which consists in firing the article to a degree of vitrification approaching fusion in a furnace or kiln having a constant flow of a temperature modifying current of air by heating the article to a temperature close to but below surface fusing temperature and maintaining such temperature for a predetermined period of time, then abruptly raising the temperature to a degree above the surface fusing point and maintaining the same until the desired surface characteristics are produced, and then increasing the air flow and abruptly reducing the temperature to a degree below the surface fusing point.

6. The method of furnace or kiln firing porcelains of the self-glazing type for the development of desired surface characteristics, which consists in firing the article in a furnace or kiln in the presence of a constantly flowing current of air to a temperature close to but below surface fusing temperature and maintaining such temperature for a predetermined period of time; then reducing the flow of air and abruptly raising the temperature of the kiln to a degree above the surface fusing temperature and maintaining such temperature until the desired surface characteristics are produced, and then increasing the air flow and abruptly reducing the temperature to a degree below the surface fusing point.

7. The method of furnace or kiln firing porcelains of the self-glazing type in a kiln or furnace for the development of desired surface characteristics, which consists in introducing fuel with a current of air together with an auxiliary temperature modifying current of air into the kiln and heating the article to a temperature close to but below surface fusing temperature for a given period

of time, then decreasing the auxiliary current of air and increasing the supply of fuel to abruptly raise the temperature to a degree above surface fusing temperature for a short period and until the desired surface characteristics are produced, and then reducing the supply of fuel and increasing the flow of the auxiliary current of air to abruptly reduce the temperature to a degree below the surface
10 fusing point.

In testimony whereof I affix my signature.
ARTHUR S. WATTS.
